UNITED STATES PATENT OFFICE.

THEODOR HEMBERGER, OF ST. LOUIS, MISSOURI.

SNARE FOR DRUMS OR OTHER MUSICAL INSTRUMENTS.

No. 899,450.

Specification of Letters Patent.

Patented Sept. 22, 1908.

Application filed December 24, 1907. Serial No. 407,906.

To all whom it may concern:

Be it known that I, THEODOR HEMBERGER, a citizen of the United States, residing at the city of St. Louis, State of Missouri, have invented a certain new and useful Improvement in Snare for Drums or other Musical Instruments, of which the following is a specification, reference being had to the accompanying drawings, forming part of this specification, in which—

Figure 1 is a top plan view of a drum embodying my invention, portions being broken away to more clearly show certain details of construction; Fig. 2 is a side elevational view, partly in section, of said drum; Fig. 3 is a sectional view on line 5—5, Fig. 2; Fig. 4 is an enlarged detail sectional view on line 6—6, Fig. 1; Fig. 5 is a fragmentary plan view of the bottom clamping-ring, showing the arrangement of the sounding or tuning string and the adjusting device therefor; Fig. 6 is an elevational view of one of the string-supporting blocks; and Fig. 7 is an elevational view of the opposite side of said supporting block.

This invention relates to a new and useful improvement in musical drums.

The object of my invention is to provide a drum with snares which can be readily moved away from the drum-head, whereby the sound of the drum may be quickly muffled or subdued and the duration of the tone shortened, and the tension of which snares or sounding-wire or wires may be easily and quickly adjusted to regulate the pitch of the drum.

With this object in view, my invention consists in the novel construction, arrangement, and combination of the several parts, all as will hereinafter be described and pointed out in the claims.

I have shown and described my improved drum-snare herein in connection with an improved construction of musical drum with which I have heretofore used my snare, but it is evident that my said snare can be as well used with other musical instruments and with drums of other constructions; and while I have shown and described my said improved drum herein, the same is not claimed here, but is claimed by me in a separate application filed March 9, 1908, and serially numbered 419,980.

In the drawings, 1 indicates the hollow cy-

lindrical body portion of the drum, on the ends of which are adapted to be mounted the heads 2 and 3, respectively. As the head 3 is similar to head 2, the description of head 2 will also apply to head 3. The drum-head 2 consists of a ring or frame 2^a, preferably of aluminum, around which the skin or vellum portion of the head is folded while wet and allowed to stretch and dry thereon, said ring forming a retaining or supporting frame for said skin or vellum.

The edges of the body portion 1 are preferably folded inwardly, as at 1^a, to form a rounded, smooth edge, which will not injure or cut the drum-heads 2 and 3 when in position thereon, the folding-in of said edges also serving to stiffen said body portion. Over said heads 2 and 3 are designed to be placed clamping-rings 4 and 5, respectively. Rings 4 and 5 are substantially U-shaped in cross-section, the inner flanges thereof, which rest upon and bear against the said heads, being preferably roughened or knurled, as at 4^a, Fig. 7, so as to securely grip the edges of said heads 2 and 3. The outer flanges of said rings 4 and 5 are provided to avoid a sharp edge which the base webs of said rings would otherwise present. Around said body portion 1 and a short distance from the top and bottom thereof are rings 6 and 7, in the form of angle-irons, which are riveted to said body portion 1, as shown in Fig. 2. The horizontal flanges of said rings 6 and 7 are provided with threaded openings 8 to receive securing-screws 9 fitting in perforations or openings in the rings 4 and 5, the screws 9 being preferably provided with angular or square heads, so that they may be readily adjusted.

On the clamping-ring 4 are strap-attaching lugs or eyes 12 for receiving a strap for supporting said drum, and mounted on the ring 7 is a block 10, pivotally mounted on which is a yoke 11 for bearing or resting against the leg of the user of the drum. Fitting in an opening in the body-portion of said yoke is a spring-pressed sliding-bolt 13, which is adapted to enter pockets 14 or 15 in said block 10, so as to hold said yoke firmly in closed or open and operative position. The bolt 13 is provided preferably with a squared body portion 13^a, which is adapted to fit in a rectangular opening 11^a in said yoke 11, said portion 13^a of the bolt 13 having a hori-

horizontal lip or portion 13^b, whereby said bolt 13 may be easily operated. The yoke 11, in Fig. 5, is shown in full lines in closed or inoperative position, and in dotted lines in open or operative position. When the drum is used as a concert or kettle-drum, the yoke 11 is kept in closed position, the bolt 13 entering the pocket 14; when the drum is used as a side drum, the bolt 13 is released from the pocket 14 and forced into pocket 15, whereby said yoke 11 is held in horizontal position and forms a body rest or support for the drum, the inner side of said yoke being provided with felt or other cushioning material 11^b.

Fitting in pockets 16 formed by the ribs 16^a in the clamping-ring 5 are slidably mounted snare-holders or string-supports 17. Supports 17 are preferably angular metallic blocks having laterally projecting portions 17^a at the upper end thereof. The outer face of each of said blocks is grooved, as at 17^b, and mounted therein are anti-friction rollers 18, around which the snare or sounding or tuning-string 19 is adapted to be passed. At one side, each of said blocks or supports 17 is provided with an opening 17^c, in which is mounted a spindle 20, to which spindles the ends of said string 19 are adapted to be attached and upon which said string is adapted to be wound in tightening said string. On the upper end of each of said spindles 20 is fastened or secured a gear-wheel 21, which meshes with a worm-screw 22, on the end of which worm-screw is a knob or screw-head 23, by which said screw may be rotated. The string 19, being attached at its ends to said spindles 20, which spindles are at opposite ends of said blocks 17 when said blocks are in position in said clamping ring 5, is arranged or passes alternately around the rollers 18 in said blocks 17, forming practically a set of wires, as shown in Fig. 7 or in dotted lines in Fig. 1. For the string 19 I prefer to use a silk and silver wire string closely woven, having a pitch close to pitch D, but, of course, other wires having other pitches may also be used. By rotating either or both of the screws 22, the motion thereof is transmitted through the gear-wheels 21 to the spindles 20, whereby the string 19 is easily wound or unwound on said spindles and the tension of said string quickly and readily regulated. As said string or snare 19 is attached at its ends to the spindles 20, the turning of either or both of said screws 22 effects what might be called a compensating lateral adjustment of the tension of said snare extending equally throughout its length. As I preferably use a wire snare or string, the greater the tension of said string, the more resonant and clearer the tone of said drum. The inner face of each of said blocks 17 is provided with suitable openings 17^d (see Fig. 9), which com-

municate with the groove 17^b to allow for the passage of the string 19 between the blocks 17, and the top of each of said blocks or supports 17 is covered by a suitable plate 17^e (see Fig. 7).

The inner flange of ring 5 is cut away as at 5^a, Fig. 7, so as to allow the string or snare 19 to rest close up against the bottom drum-head 3, as shown in Fig. 6, which is its normal position, thereby giving the drum a good, clear sound; but should it be desired to muffle or subdue the sound or tone of the drum, the blocks or supports 17 are easily moved or slid downwardly in the pockets 16 away from the drum-head 3, so as also to carry the string 19 away from said drum-head, as shown by dotted lines in Fig. 6. When the string 19 is away from said drum-head, the tone of the drum is muffled or subdued, as is well understood; when it is desired to again increase the tone or, rather, make the tone of the drum louder, the blocks or supports 17 and also the string 19 carried thereby are readily moved close up against the drum-head 3. The tension of the string 19 is sufficient to firmly hold the blocks or supports 17 in any position in which they may be placed. As is usual, the body portion 1 of the drum is provided with a sounding-hole 24, and the supports 17 are so placed in the ring 5 as to hold the string 19 across the drum-head 3 at what might be called right-angles to said sounding-hole.

By the construction of drum described, it will be obvious that my drum can be used as a kettle, concert, or side drum. It is further seen that the tension of the sounding or tuning string 19, which string has also a great deal to do in giving the drum a good, clear tone, is quickly and readily regulated, and the sound of said drum can be at once subdued or muffled, as before described, whenever desired. I have found that the sound or tone of my drum provided with my improved snare is about four times as loud as that of any other drum now on the market.

It will also be plain that minor changes in the arrangement, construction, and combination of the several parts of my snare may be made and substituted for those herein shown and described without in the least departing from the principle of my invention.

Having thus described my invention, what I claim and desire to secure by Letters Patent is:

1. The combination with a drum, of a snare, and snare-holders suitably mounted on said drum and to which the ends of said snare are attached, one or both of said snare-holders being rotatable, whereby the tension of said snare may be adjusted; substantially as described.

2. The combination with a drum, of a snare, snare-holders slidably mounted on said drum, and rotatable means in said snare-

holders to which the ends of said snare are attached, whereby the rotation thereof regulates the tension of said snare.

3. The combination with a drum, of a snare, and snare-holders slidably mounted on said drum for movably supporting said snare, said snare-holders being held in adjusted positions by the tension of said snare; substantially as described.

10 4. The combination with a drum, of a snare, snare-holders slidably mounted on said drum for movably supporting said snare, said snare-holders being held in their several positions by the tension of said snare, and 15 means for regulating the tension of said snare; substantially as described.

5 The combination with a drum, of snare-holders mounted thereon, a snare supported by said snare-holders and extending alternately from one snare-holder to the other, whereby a continuous set of snares is provided, and means at the end of said snare for effecting an adjustment of the tension of said snare extending throughout its length; substantially as described.

20 6. The combination with a drum, of a snare, snare-holders, spindles in said holders to which the ends of said snare are attached, and means for rotating said spindles, whereby 30 the tension of said snare is regulated; substantially as described.

7. The combination with a drum, of a snare, snare-holders, spindles in said holders to which the ends of said wire are attached, and gear mechanism meshing with said spindles for rotating the same, whereby the tension of said snare is regulated; substantially as described.

8. In a musical drum, the combination 40 with a body portion, of a drum-head, a sounding-string, blocks for supporting said string, a spindle in each of said blocks to which the ends of said string are attached, and means for rotating said spindles, whereby 45 the tension of said string is regulated; substantially as described.

9. In a musical drum, the combination with a body portion, of a drum-head, a sounding string, blocks for supporting said string, spindles in said blocks to which the ends of said string are attached, gear-wheels on said spindles, and worm-screws meshing with said gear-wheels, whereby the rotation of said screws regulates the tension of said 55 string; substantially as described.

10. In a musical drum, the combination with a body portion, of a drum-head, a sounding string, blocks for supporting said string, spindles in said blocks to which the

ends of said string are attached, anti-friction 60 rollers mounted in said blocks and around which said string passes, and means connected to said spindles for rotating the same, whereby the tension of said string is regulated; substantially as described.

65 11. The combination with a drum, of a snare, snare-holders, spindles in said snare-holders to which the ends of said snare are attached, rollers mounted in said snare-holders and around which said snare passes, 70 and gear mechanism meshing with said spindles, whereby the tension of said snare is adjusted; substantially as described.

75 12. In a musical drum, the combination with the body portion thereof, of a drum-head, a clamping-ring for holding said head in position, a snare, snare-holders slidably mounted on said ring for movably supporting said snare, and gear mechanism on said snare-holders for regulating the tension of said 80 snare; substantially as described.

85 13. In a musical instrument, the combination with a hollow cylindrical body portion, of a skin-head therefor, a ring for holding said head in position on said body portion, pockets in said ring, a snare extending across said head, and snare-holders slidably mounted in said pockets for movably supporting said snare; substantially as described.

90 14. In a musical instrument, the combination with a cylindrical body portion, of a skin-head therefor, a ring for holding said head in position on said body portion, a snare extending across said head, and snare-holders slidably mounted on said ring, said snare-holders being held in adjusted positions by the tension of said snare; substantially as described.

95 15. In a musical instrument, the combination with a cylindrical body portion, of a skin-head therefor, a ring for holding said head in position on said body portion, snare-holders mounted on said ring, a string supported by said snare-holders and extending alternately from one snare-holder to the other, whereby a continuous set of strings for said head is provided, and means engaging the end of said snare for effecting an adjustment of the tension of said string extending throughout its length; substantially as 105 described.

In testimony whereof, I have signed my name to this specification in the presence of two subscribing witnesses.

THEODOR HEMBERGER.
